DESIGN FOR A MILLINERY DISPLAY STAND

Jeannette E. Yost, Canton, Ohio

Application November 23, 1944, Serial No. 116,514

Term of patent 7 years

(Cl. D80—8)

To all whom it may concern:

Be it known that I, Jeannette E. Yost, a citizen of the United States, residing at Canton, in the county of Stark and State of Ohio, have invented a new, original, and ornamental Design for a Millinery Display Stand, of which the following is a specification, reference being had to the accompanying drawing, forming part thereof.

Fig. 2 is a front elevation thereof.

I claim:

The ornamental design for a millinery display stand, substantially as shown.

JEANNETTE E. YOST.
